Patented Mar. 14, 1922.

UNITED STATES PATENT OFFICE.

LOUIS T. SCHUBERTH, OF CHICAGO, ILLINOIS.

BOTTLE RECEPTACLE.

1,409,416.

Specification of Letters Patent Patented Mar. 14, 1922.

Application filed January 24, 1921. Serial No. 439,408.

To all whom it may concern:

Be it known that I, LOUIS T. SCHUBERTH, a citizen of the United States, and resident of Chicago, in the county of Cook and State 5 of Illinois, have invented certain new and useful Improvements in a Bottle Receptacle, of which the following is a specification.

My invention relates to a milk bottle safe or receptacle adapted to receive a bottle of 10 milk from the exterior and when closed to prevent the removal of the bottle except from the interior.

One of the objects of the invention is to provide a device of simple construction so arranged as to adapt itself to the reception of one or more bottles and to be locked in position by the weight of the bottles. The device is an improvement on those locking receptacles in which the shape or size of the 20 bottle is an important element in the locking means. The present device depends wholly on the weight of the bottle for retaining the outside closure in locked position.

The invention will be more readily understood by reference to the accompanying drawings, in which,

Fig. 1 is a vertical sectional view through a device constructed in accordance with my invention, the parts being shown in position 30 to receive a bottle of milk;

Fig. 2 is a similar view showing the device in closed position; and

Fig. 3 is a sectional view on the line 3—3 of Fig. 2.

In the drawings it will be seen that the 35 device comprises side walls 10 and top and bottom walls 11, 12. When complete front and rear walls 13, 14 are employed, the door or closure 15 for the outside opening being 40 hinged or pivoted as at 16, to the wall 13. The box formed by the walls described, may be secured to a wall adjacent to a window or door as desired, a hinged window 17 being shown in Fig. 1.

The door or closure 15 is provided at its 45 lower end with lateral, inwardly extending arms 18, to which is pivoted a bottle supporting member 19. The pivot 20, of this member, is positioned intermediate the ends 50 of the support and is so arranged relative to the weight of the support that there is a preponderance of weight outside of the pivot. This weight preponderance may be secured by providing a casting 21, which is 55 in effect a counter-weight, the casting having ears 22, which in conjunction with a pin 23

serves to connect the support to a vertical latch 24, set into the closure. The latch or bar 24 may be held in position by the cross straps 25. At its upper end the latch is suitably beveled to engage behind a stop 26, whereby the door may close notwithstanding an elevated position of the latch. In operation the device may be positioned as shown in Fig. 1. A bottle 27 is placed upon the 60 door and the door then swung into its closed position. The weight of the bottle being transmitted to the support will tend to force the latch into its locking position and when 65 closed it will be seen that the door cannot be opened from the outside. Immediately, however, upon removal of the bottle from the inside the over-balanced weight of the support will move the latch to unlocked position and the door will swing open.

Obviously the construction is capable of much modification and I do not wish to be limited except as indicated in the appended claims:

I claim:

1. A device of the class described comprising in combination, a box having an outside opening, a closure pivoted near its lower end for closing said opening, a bottle-supporting member pivoted to the closure at a point inside of the box, and a latch cooperating with said supporting member and adapted to be moved and held in position to lock said closure in closed position by the weight of a bottle on said member.

2. A device of the class described comprising in combination, a box having an outside opening, a door for said opening, a bottle-support pivoted to the door, and a door latch cooperating with said support and adapted to be moved to locking position by the weight of a bottle on said support.

3. In a milk bottle safe, the combination of a box having an outside opening, a door for said opening, mounted on a horizontal pivot located near the lower extremity of the door, arms connected to the door and projecting inwardly of the door, a bottle-support pivoted to said arms at a point intermediate the ends of the support, and a latch for the door adapted to be moved to closed position by the weight of a bottle on said support.

4. In a milk bottle safe, the combination of a box having an outside opening, a door for said opening, mounted on a horizontal pivot located near the lower extremity of

the door, arms connected to the door and projecting inwardly to the door, a bottle-support pivoted to said arms at such a point as to provide a preponderance of weight 5 outside of the pivotal point, and a door latch connected to the support and adapted to be moved into and out of locking position by movement of said support.

5. A locking device for bottles comprising 10 in combination, walls providing front and rear openings, said front opening having a door pivoted near its lower end on a horizontal pivot, arms projecting laterally in-

wardly from said door, a bottle-supporting and locking member pivoted to said arms, a 15 counter-weight secured to said member outwardly of said pivot, and a latch connected to the member whereby said latch is normally held in unlocked position by the overbalanced weight of said member, said latch 20 being moved into locked position by the weight of a bottle on said member.

Signed at Chicago, Illinois, this 19th day of January, 1921.

LOUIS T. SCHUBERTH.
